Primary Examiner — Carla Jobe Wright

CLAIM

The ornamental design for an electronic device shell, as shown and described.

DESCRIPTION

FIG. 1 is a front perspective view of an electronic device shell showing the Applicant's new design;

FIG. 2 is another front perspective view thereof;

FIG. 3 is a rear perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

1 Claim, 7 Drawing Sheets
